UNITED STATES PATENT OFFICE.

CHARLES L. REED, OF ROCHESTER, NEW YORK.

FUEL MIXER FOR INTERNAL-COMBUSTION ENGINES.

Application filed March 25, 1921. Serial No. 455,560.

To all whom it may concern:

Be it known that I, CHARLES L. REED, a citizen of the United States, and resident of Rochester, in the county of Monroe and State of New York, have invented certain new and useful Improvements in Fuel Mixers for Internal-Combustion Engines, of which the following is a specification.

The present invention relates to fuel mixers for internal combustion engines, and an object thereof is to provide for mixing the fuel delivered to an internal combustion engine so that a more effective operation of the engine is secured. Another object of the invention is to provide a simple and inexpensive means for utilizing the exhaust gases from the explosive engine for the purpose of heating the fuel delivered to the engine.

To these and other ends the invention consists of certain parts and combinations of parts, all of which will be hereinafter described, the novel features being pointed out in the appended claims.

In the drawings:

Fig. 1 shows a fragment of an explosive engine of the type used in the Ford automobile, the present invention being incorporated therein;

Fig. 2 is a fragmentary view partially in section showing the manner in which the exhaust manifold and the intake manifold are associated with the present invention;

Fig. 3 is an enlarged face view with the parts broken away, showing the chambered member;

Fig. 4 is a section on the line 4—4, Fig. 3;

Fig. 5 is a detail sectional view showing the manner in which the exhaust manifold connects with the chambered member;

Fig. 6 is a detail view showing the manner in which the intake manifold connects with the chambered member;

Fig. 7 is a detail sectional view of the connection between the chambered member and the member which encloses the intake manifold; and

Fig. 8 is a detail view of another embodiment in which the heating coil is on the inner side of the mixing device.

Referring more particularly to the drawings, 1 indicates an engine body or casing which is of known construction and has four chambers 2, each of which has leading thereto, an exhaust valve chamber 3 and an in-

let valve chamber 4. The adjacent inlet valve chambers 4 have a common inlet opening 5, while the exhaust valve chambers 3 have individual outlet openings 6. The manifold 7 leading from the carburetor, not shown, has two branches as is common, connecting with the inlet openings 5, while the exhaust manifold 8 has four branches as is common, connecting with the exhaust openings 6. These manifolds are held in position as is common, by clamping pieces 9 secured to anchor bolts 10, which are, in this embodiment, longer than the usual anchor bolts.

With the end in view of heating the gases passing from the manifold into the inlet valve chambers and at the same time, effecting a thorough mixture of the constituents of said gases, there is provided preferably between the manifold and the body 1 of the engine, a mixing device preferably similar to that disclosed in my U. S. Patent No. 1,300,015, granted April 8, 1919, and embodying a plurality of non-moving twisted blades 11 secured to each other in an axial line and each gradually decreasing in width toward its outer end. The mixing device is arranged within a collar or sleeve 12 and preferably is also combined with a spirally formed coil 13 connected by terminals 31

with any suitable electric source, such as the batteries of the explosive engine. This coil may be arranged either on the outer side of the mixing device as illustrated in Figs. 3, 4 and 6, or on the inner side of the mixing device as illustrated at 13^a in Fig. 8. This coil is designed for heating the gas on the starting of the engine and when used during the usual running of the motor, it will heat the gas and effect a still further mixture in combination with the mixing device.

Also associated with the sleeve or tube 12 which forms a part of the passageway between the carburetor and the engine is a heating means preferably in the form of a chambered member which receives exhaust gases from the exhaust of the engine. This chambered member, in this instance, is formed by two sheets of material 14, pressed in opposite directions to provide a chamber 15 between them, the edges of the sheets being welded or otherwise secured together at 16. The tube or sleeving 12 connects the opposite walls of the chamber and is provided with two flanges 12^a which have the

dual function of separating the walls of the chambered member and also of conducting heat from the chambered member to the sleeve 12. The position of this sleeve 12 is, in this instance substantially midway between the ends of the chamber which is of elongated form, passageway being provided about the sleeve from one end of the chamber to the other. One chambered member is provided for each inlet opening 5 and the two adjacent exhaust openings 6. The chambered member also has two sleeves or tubes 17 connecting opposite walls thereof on opposite sides of the sleeve 12 and forming parts of the two exhaust passageways, establishing connection between the exhaust openings 6 and the exhaust manifold 8. Each of these sleeves or tubes 17 is provided with two surrounding flanges 18 and serving to space said walls apart.

With the end in view of providing communication between the exhaust passageways and the chamber 15, the sleeves 17 are provided with lateral ports 19 between the flanges 18, these ports opening to the chamber 15, and the chamber 15 being provided with an outlet opening 20. By this arrangement, a circulation is created through the chamber 15 about the sleeve 12 due to the fact that when pressure exists in one of the sleeves 17, a reduction in pressure will take place in the other sleeve, thus causing the exhaust gases to flow through the outlet 20, which, in order to maintain a pressure in the chamber 15, is smaller than the openings or ports 19.

Each chambered member is supported on two of the anchoring studs or pins 10 and to this end each chamber is provided with openings through which the pins extend, these openings, in this instance, being formed by providing sleeves 21 connecting opposite walls of the chamber 15. The ends of the sleeves 12 and 17 project beyond the chambered member and are seated in the annular recesses 22 about the inlet and exhaust openings 5 and 6, as well as in the annular recesses 23 in the inlet and exhaust manifolds 7 and 8. The clamping members 9 which are secured to the studs 10, hold the inlet and exhaust manifolds against the chambered member and the flanges on the sleeves 12 and 17 prevent the distortion of the walls of the chambered member under the pressure of the clamping devices.

With the purpose in view of heating the intake manifold, there may be provided a chamber about said manifold connecting with the chambered member 15. This manifold enclosing chamber comprises a back plate 24 arranged in rear of the manifold and a front member 25 secured to the back plate by fastening devices 26. The back plate has an inlet opening formed in a sleeve 27 pressed from such back plate and

engaging the nipple 28 formed about the outlet opening 20 as shown in Fig. 7 of the drawings. This manifold enclosing chamber communicates with both of the chambers 15 so that the exhaust gases from said chambers pass into the chambered member about the manifold and heat the latter. An outlet or tube 29 depends from the lower portion of the manifold enclosing chamber and is carried by a plate 30 which is secured about the lower portion of the manifold. Packing 31 surrounds the three arms of the manifold so as to prevent the escape of the exhaust gases except through the tubing 29. This tubing also permits the discharge of the carbon forming in the manifold enclosing chamber, as well as in the chambers 15.

The operation of the invention will be understood from the foregoing description, but it may be summarized as follows:

In starting the engine, the coils 13 are heated from the battery and after the engine has started, the exhaust gases will pass from the exhaust passageways into the chambers 15, thus heating the tubing 12 which will by conduction, heat the bladed mixing device 11. The exhaust gases passing from the chambers 15 through the outlet will then pass into the manifold enclosing chamber and heat the manifold and from the latter will be discharged to the atmosphere. The circuitous path which the exhaust gases must take, muffles the exhaust sound. As each chamber 15 receives exhaust gases alternately from two of the exhaust ports, one of such ports does not retard the flow of gas through the chamber while the other is active.

From the foregoing it will be seen that there has been provided an effective means for heating and mixing the gases fed to an explosive engine. Means is provided which conducts the exhaust gases about a sleeve or tubular member through which the fuel travels, this tubular member having therein, a mixing device which effectively mixes the gases and is at the same time heated by the exhaust gases. This result is secured, in this instance, by a chambered member which is adapted to be arranged between the intake and the exhaust manifold for the purpose of conducting the exhaust gases about the intake passageway which leads through the chambered member. This chambered member is adapted for attachment to the ordinary motor without making any material changes therein. Means is also provided for heating the intake manifold in an effective way from the exhaust gases.

What I claim as my invention and desire to secure by Letters Patent is:

1. A fuel mixer comprising a chamber having an inlet passageway and two exhaust

passageways on opposite sides of the inlet passageway, each passageway entering through one wall of the chamber and out through the opposite wall in line with its entrance, the inlet passageway being closed to the chamber and the exhaust passageways, each opening to the chamber.

2. The combination with an explosive engine having a detachable intake manifold and a detachable exhaust manifold, of a chambered device arranged between the two manifolds and the inlet and exhaust openings of the engine, said chambered device having at least two passageways therethrough, one of which connects the intake manifold with the engine and the other of which connects the engine with the exhaust manifold, the last named passageway having an opening communicating with the chamber of the device so that exhaust gases may pass into the chamber about the passageway connecting the intake manifold with the engine.

3. The combination with an explosive engine having two cylinders, the casing of the engine being provided with a common inlet port for the two cylinders, and separate exhaust ports, one for each cylinder situated on opposite sides of the inlet port, of a chambered member having three passageways therethrough, one connecting with the inlet port and the other two connecting with the exhaust ports and each having an opening communicating with the chamber to supply the exhaust gases thereto for heating the inlet passageway of the chambered member, and detachable inlet and exhaust manifolds connected with the passageways.

4. A fuel mixing device comprising a chambered member, a flanged sleeve con-

necting opposite walls of said member and projecting from opposite sides thereof to form an inlet passageway, and two flanged sleeves connecting the two walls and projecting from opposite sides thereof to form an exhaust passageway, said last mentioned sleeves having openings between the flanges communicating with the chamber.

5. A fuel mixing device comprising a chambered member, a flanged sleeve connecting opposite walls of said member and projecting from opposite sides thereof to form an inlet passageway, and two flanged sleeves connecting the two walls and projecting from opposite sides thereof to form an exhaust passageway, said last mentioned sleeves having openings between the flanges communicating with the chamber, and a fuel mixing device arranged in the inlet passageway and receiving heat from the walls of said passageway.

6. The combination with an explosive engine having an intake port and an exhaust port, a detachable intake manifold, and a detachable exhaust manifold, of a chambered member interposed between the two manifolds and the ports in the engine having a passageway therethrough connecting the intake manifold with the engine, and having a passageway therethrough connecting the engine with the exhaust manifold, said last named passageway having an opening communicating with the chamber of the chambered member, and a chamber surrounding the intake manifold and communicating with the chamber of the chambered member to receive exhaust gases from the latter.

CHARLES L. REED.
